UNITED STATES PATENT OFFICE.

GEORGE R. RICH, OF LOS ANGELES, CALIFORNIA.

VALVE TAPPET FOR INTERNAL-COMBUSTION ENGINES.

Application filed September 23, 1922. Serial No. 590,026.

To all whom it may concern:

Be it known that I, GEORGE R. RICH, a citizen of the United States, and a resident of Los Angeles, Los Angeles County, and 5 State of California, have invented certain new and useful Improvements in Valve Tappets for Internal-Combustion Engines, of which the following is declared to be a full, clear, and exact description.

10 This invention relates to valve tappets for internal combustion engines, and its principal object is to provide means for compensating for any misalignment of the cam shaft, or the tappets of internal combustion engines, whereby the cams may contact 15 squarely across the faces of the tappet heads. Much difficulty has been encountered in the cam shaft and tappet assemblies, due to the fact that it is practically impossible to 20 grind the cam shafts perfectly true, and like-wise practically impossible to install the cam shafts perfectly true, owing to slight misalignment of the bearings. The greatest difficulty arises in installing the tappets in 25 true relation to the cam shaft—that is to say in installing them at perfect right angles to the cam shaft. When it is realized that the bushing in which the tappet moves, must have some clearance when inserted, there is 30 no assurance that it is at a perfect right angle to the cam shaft when tightened in place. The result is that when the cam shaft and a tappet are not accurately located at right angles to each other, one extreme corner of 35 the cam only, engages the tappet and causes the same to wear away rapidly, especially where it will operate in one position for some length of time. Often it wears a depression in the face of the tappet, and when 40 the tappet turns around in its bushing, a high place is presented to the cam, causing improper adjustment between the valve and tappet.

In accordance with the present invention, 45 I provide a tappet head which is capable of angular movement relative to the body or stem of the tappet, whereby the head may align itself properly with respect to the cam, so that the full face of the latter may 50 bear against the face of the tappet head, irrespective of any slight misalignment of the cam shaft or tappet. This I have accomplished by swiveling the head upon the tappet body or stem on a line running crosswise 55 of the axis of the cam shaft whereby the face of the tappet head may assume a plane

parallel with the axis of the cam shaft despite any misalignment of the cam shaft or tappet body.

The invention consists in a tappet having 60 a head separate from the body and swiveled thereto on a line running crosswise of the cam shaft, whereby the cam may track squarely across the face of said tappet head. The invention further consists in the several 65 novel features hereinafter fully set forth and claimed.

The invention is clearly illustrated in the drawing accompanying this specification, in 70

Fig. 1 is a view partly in side elevation and partly in central, vertical section of a valve tappet assembly and fragment of a cam shaft, illustrating one embodiment of the invention; Fig. 2 is a vertical section taken on line 2—2 of Fig. 1 and showing the bushing and a part of the tappet in elevation; Fig. 3 is a cross section taken on the line 3—3 of Fig. 1, and Fig. 4 is a side elevation of the tappet.

Referring to said drawing, the reference character 10 designates a fragment of a cam shaft of an internal combustion engine, and 11 designates one of the cams thereon. Above 75 the cam, and extending approximately at right angles to the cam shaft is a bushing 12 which is stationarily secured in the motor block (a) as usual. These parts are well known and require no particular description 80 so far as this specification is concerned.

Extending through the bore of the bushing 85 is the tappet body or stem 14 which, in the form illustrated, is centrally bored and tapped as usual for the reception of the adjusting stud (not shown). The tappet head 15 is formed of a separate piece of material 90 and has the usual disk like head portion 16 formed with a flat face 17 that is engaged by the cam face 18 of the cam 11. The tappet head 15 is swiveled or otherwise connected to the body 14 in such manner as to admit of angular movement of the head with respect to the body, and as shown, the body is centrally slotted lengthwise of itself, to 95 leave furcations or forks 19, between which is an ear or lug 20 formed on the head portion 16. A pin 21 extends through apertures in the forks 19, and ear or lug 20 and pivotally connects the head with the body. To 100 prevent the tappet from turning in its bushing, the lower end portion of the bushing is 105 slotted lengthwise of itself to leave furca-

tions or forks 22, and the ear or lug 20 is made a trifle wider than the body portion of the tappet and projects into the slot between the forks 22. The head and body are 5 held by said forks 22 against turning in the bushing.

In operation the tappet is held down against the cam by the valve spring (not shown) as is well understood. In case the 10 body or stem 14 is not located precisely at right angles to the cam shaft, the tappet head adjusts itself, under the influence of the cam, so that the face of the head is brought parallel with the face of the cam, 15 thereby permitting the cam to track squarely across the face of the tappet. The wear on the faces of the cam and tappet head is spread over the entire contacting surfaces and the possibility of cutting grooves in the 20 head is thereby eliminated.

More or less variation of the exact details of construction is possible without departing from the spirit of this invention; I desire, therefore, not to limit myself to the exact 25 form of the construction shown and described, but intend, in the following claims, to point out all of the invention disclosed herein.

I claim as new and desire to secure by 30 Letters Patent:

1. A valve tappet, comprising a tappet body and a separate tappet head swiveled thereto on a line running crosswise of an associated cam shaft, whereby the head may 35 adjust itself to engage the cam squarely across its face.

2. A valve tappet, comprising a tappet body and a separate tappet head movable relative to the body in a plane parallel to 40 the axis of an associated cam shaft, whereby the head may adjust itself to engage an associated cam squarely across the face of the cam.

3. A valve tappet, comprising a tappet 45 body and a separate tappet head fulcrumed

thereon on a line running crosswise of an associated cam shaft, whereby said head may adjust itself to engage an associated cam squarely across its face thereof.

4. A valve tappet, comprising a tappet 50 body, a separate tappet head, and a pivot pin connecting said body and head, said pivot pin extending crosswise of an associated cam shaft.

5. A valve tappet, comprising a tappet 55 body forked at its lower end, a tappet head having an ear located between said forks, and a pivot pin extending through said forks and ear, said pin extending crosswise of an associated cam shaft.

6. A valve tappet, comprising a tappet body and a separate tappet head swiveled thereto on a line running crosswise of an associated cam shaft, whereby the head may 60 adjust itself to engage the cam squarely across its face, and means for securing said tappet against rotation.

7. A valve tappet, comprising a tappet body, a separate tappet head and a pivot pin connecting said body and head, said pivot 70 pin extending crosswise of an associate cam shaft and means for securing said tappet against rotation.

8. A tappet assembly, comprising a bushing, a tappet mounted therein and having a 75 separately formed disc like head swiveled thereto on an axis running crosswise of an associated cam shaft, and coacting means between the bushing and tappet for preventing 80 relative rotation between them.

9. A tappet assembly, comprising a bushing having a forked lower end, a tappet body mounted therein and having a forked lower end, and a disc like tappet head having an 85 ear extending between the forks of the bushing and tappet body and pivotally connected to said tappet body on a line running crosswise of an associated cam shaft.

GEORGE R. RICH.
